The ornamental design for a accessory bracket for fiber management, as shown.

DESCRIPTION

FIG. 1 is an isometric view of the design for an accessory bracket for fiber management in accordance with a preferred embodiment of the present invention;

FIG. 2 is a front elevational view of the accessory bracket for fiber management of FIG. 1;

FIG. 3 is a left elevational view of the accessory bracket for fiber management of FIG. 1;

FIG. 4 is a right elevational view of the accessory bracket for fiber management of FIG. 1;

FIG. 5 is a top plan view of the accessory bracket for fiber management of FIG. 1;

FIG. 6 is a bottom plan view of the accessory bracket for fiber management of FIG. 1; and,

FIG. 7 is a rear elevational view of the accessory bracket for fiber management of FIG. 1.
